United States Patent Office

Des. 210,906
Patented Apr. 30, 1968

210,906

LIGHTER

Teruo Sakabe, Tokyo-to, Japan, assignor to Kabushiki
Kaisha Crown Sangyo, Tokyo-to, Japan

Filed May 17, 1967, Ser. No. 7,158

Claims priority, application Japan Nov. 26, 1966

Term of patent 14 years

(Cl. D48—27)

FIG. 1 is a front elevational view of a lighter.

FIG. 2 is a plan view thereof.

FIG. 3 is a bottom view thereof.

FIG. 4 is a side elevational view of one side thereof.

FIG. 5 is a side elevational view of the other side thereof.

FIG. 6 is a perspective view thereof.

The rear elevational view is omitted since it is symmetrical with the front elevational view.

I claim:

The ornamental design for a lighter, as shown and described.
